SNAP-ACTING FLUID METERING VALVE DEVICE

Joseph T. Abdo, Minneapolis, Minn., assignor to Minneapolis-Honeywell Regulator Company, Minneapolis, Minn., a corporation of Delaware

Application September 30, 1950, Serial No. 187,751

12 Claims. (Cl. 251—13)

This invention relates to fluid metering means and, more particularly, to metering means for delivering oil to an oil burner at a uniform rate.

Prior art arrangements for delivering oil to a burner have generally taken the form of a constant level oil valve wherein the fluid or oil is maintained at a predetermined elevation above the oil outlet in the burner with the rate of fluid flow from said constant level valve controlled by a needle valve. Unless this type of valve is also provided with complicated and costly means to compensate for variations in the oil temperature, the changing viscosity of the oil materially affects the rate of oil flow and, consequently, the heat output of the burner.

Another type of oil metering means in general use has been a device wherein a pressure regulator, receiving oil from a positive displacement pump, maintains the pressure of the oil at the burner at substantially a uniform pressure. Here again, with changes in temperature and viscosity, the quantity of the fuel delivered and the heat produced by the burner varies. This arrangement also requires additional compensating means to assure uniform delivery of oil regardless of temperature change.

It is an object of this invention to provide a simple, inexpensive, reliable, and compact fuel metering means that requires no complicated or expensive compensating means to assure substantially uniform fuel flow.

Another object of the invention is to provide a fuel metering means which makes use of the head of oil in the supply source to cause actuation of the metering means.

Another object of the invention is to provide a metering device of the accumulator type wherein a timing means for the discharging of fuel from said accumulator is hydraulically controlled.

A further object of the invention is to provide a metering device of the accumulator type wherein a movable wall of the accumulator actuates a snap valve that controls the inlet and outlet ports to the accumulator.

Another object of the invention is to provide a snap acting valve which is loaded in one direction only and which is actuated in its other direction by means of inlet fluid pressure acting on an actuator for said valve.

Still another object of the invention is to provide a snap acting valve which is biased in one direction constantly by a resilient means and is alternately biased in opposite directions by snap means having a bifurcated resilient reed acting on spaced actuator arms for the valve.

Another object of the invention is to provide a fuel metering device which is hydraulically controlled by a fluid the viscosity of which does not vary over wide temperature ranges.

Additional objects of the invention will become apparent upon reading the following detailed description of the invention in conjunction with the drawing wherein:

Figure 1 is a side elevational view of the metering device, partly in cross section and with a portion thereof broken away;

Figure 2 is a perspective view of the snap acting control valve with its cover removed; and

Figure 3 is a sectional view taken along the line 3—3 of Figure 2, showing the actuating lever for the control valve in another of its operating positions.

The preferred embodiment of the metering device comprises four main body portions 10, 11, 12 and 13 which are clamped together by means of bolts 14, with the portions 11, 12 and 13 additionally held together by

2

bolts 15 and the portions 10 and 11 additionally held by bolts 16 and screw 17. A diaphragm 18 is clamped circumferentially between opposed surfaces of the portions 11 and 12 while gaskets (not shown) are provided between the portions 12 and 13 and the portions 10 and 11 to provide fluid tight joints therebetween. A cover 10a is secured to the body portion 10, with a gasket (not shown) therebetween, by means of screws 19 extending through holes in the cover 10a in alignment with threaded bores 19a. Two bolts 14 extend completely through holes in body portions 11, 12 and 13 and are screw threaded into threaded bores 14a in body portion 10. Bolts 16 extend through holes in a wall of body portion 11 and are screw threaded in threaded bores 16a in body portion 10. Screw 17 extends through a flange 10b on the cover 10a and is screw threaded into body portion 11.

Body portion 10 (best seen in Figure 2 of the drawing) has a threaded inlet port 20 adapted to be connected by a pipe 21 to a source of fuel (not shown) at an elevation above that of the metering device. A fuel supply control valve 22 may be of the manually operable type or may be of the conventional safety type which is thermostatically controlled. A threaded outlet port 23 is in axial alignment with the inlet port 20 and is adapted to be connected to a burner (not shown) through a stem 24.

A valve stem 25 carries an inlet valve head 26 at one end thereof and an outlet valve head 27 at the other end thereof. Prongs 26a extending longitudinally outwardly from the heads 26 and 27, respectively, engage the inner unthreaded ends of the inlet and outlet passages 20 and 23, respectively, for holding said valve in centered position over the inner ends of said inlet and outlet, to assure proper seating thereof. It will be noted that when the valve head 27 is in seating relationship with the inner end of the outlet passage 23, the valve head 26 is raised out of seating engagement with the inner end of inlet 20 so as to permit flow of fluid through said inlet and between the prongs 26a into a chamber 28 within the body portion 10. A transversely extending arm 29 is secured to the stem 25 intermediate its end to serve as an actuating means for the valves 26 and 27.

A lever or crank 30, secured to a wall of the body portion 10 by means of a pivot 31 near one of its ends, has a slightly elongated aperture 32 therein near its free end, through which the pin 29 extends for actuation thereby. A coiled tension spring 33 normally biases the crank 30 in a direction to cause the valve 27 to close. Transversely extending arms 34 and 35 are formed on the pivoted end of the crank 30, one on each side of the pivot 31.

Cooperating with the arms 34 and 35 is a quite stiff resilient reed 36 having a bifurcated free end providing tines 36a and 36b cooperable with the arms 34 and 35, respectively. The other end of the reed is clamped in a slot 37 formed in a block 38 at an acute angle with respect to a stem 39 extending vertically through said block 38, as viewed in the drawing. The reed 36 is clamped in said slot 37 by means of screws 40 extending through aligned holes (not shown) in the block and the reed 36 and screw threaded into that portion of the block 38 on the opposite side of the reed from the screw heads. The stem 39 is guided for vertical movement by the upper end thereof extending into a bore 41 in one wall of the body portion and into a bore 42 in a boss 43 on an opposite wall of said body portion 10. To prevent rotation of the stem 39, a pin 44 is suitably secured to the stem 39 for vertical movement only in a slot 45 in the boss 43. It is thus seen that the reed 36 can travel only in a vertical direction, except for whatever horizontal movement that may be imparted to the free end thereof due to engagement of said free end with a fixed abutment as the reed moves vertically, as will obviously take place when the reed 36 moves vertically with respect to the arms 34 and 35, which action will be described hereinafter. Two spaced pins 46 are secured to and extend laterally from the stem 39 for engagement by an actuating means to be presently described.

Body portion 11, which joins the body portion 10, has a two-way fluid passage 47 providing communication between the chamber 28 of body portion 10 and

an accumulator chamber 48 formed between a side wall of the portion 11 and the diaphragm 18. A second opening 49 between the chambers 28 and 48 has a bell crank lever 50 pivoted therein. One of the arms of the bell crank lever extends between the pins 46 on the stem 49 for actuation thereof while the other arm of the bell crank lever has a bifurcated free end 51 which straddles a pin 52 on a bolt 53. The bolt 53 extends through a hole (not shown) in the center of the diaphragm 18 and clamps the center portion of said diaphragm in sealing relationship to the bolt 53 by means of washers 54. The end of the bolt 53 in the chamber 48 has an apertured lug 55 thereon which is engaged by one end of a coil spring 56 which has a low spring constant to reduce its effect on flow rate per cycle. The other end of the coil spring 56 is swivelly connected to an adjusting screw 57 extending through a packing nut 58 and screw threaded into a recessed side wall 11a of the body portion 11. By arranging the elements of the device so that the diaphragm will be horizontally disposed, a weight may be substituted for the spring 56, thus providing a constant biasing force over the entire expelling stroke of the diaphragm.

The upper portion of the body portion 12 (as viewed in the drawing) has a transversely extending bore 59 which is vented to the atmosphere through an opening 60 in the top of said bore and which communicates with a chamber 61, formed between a side wall of the body portion 12 and the diaphragm 18, by means of a passage 62. The chamber 61 is filled with glycerin or similar fluid. A ball check valve 63 permits fluid flow from chamber 61 into the bore 59 but prevents reverse flow from said bore to said chamber. A pin 64 secured to a wall of the bore 59 prevents the ball 63 from moving laterally out of position with respect to passage 62. The lower portion of the side wall of the body portion 12 has two ports 65 and 66 therein through which fluid may pass between chamber 61 and chamber 67 formed between the side wall of the body portion 13 and the side wall of body portion 12. The chamber 67 also has communication with the bore 59 through a passage 68 formed in the upper part of portion 13 and is likewise filled with the same fluid as is in chamber 61.

The body portion 13 has two bosses 69 and 70 in axial alignment with the ports 65 and 66, respectively. Threaded needle valves 71 and 72 extend through packing nuts 73 and 74, respectively, on said bosses and are adjustably threaded through bores in said bosses so as to regulate the rate of fluid flow through the ports 65 and 66 respectively. It is intended that one of the needle valves be used to provide a constant minimum flow of fuel to the burner, while the other of said needle valves is intended to be operated between a closed position and a predetermined open position, either manually or automatically, to vary the rate of flow between the chambers 67 and 61, when it is so desired.

Operation

Assuming that the metering device as shown in the drawing is connected to a source of fuel supply, such as an oil storage tank, and the conduit 24 is connected to a burner in a furnace, the elements of the device are illustrated in Figures 1 and 2 as seen in the positions they would assume near the end of the accumulator charging movement of the diaphragm 18. That is, the inlet valve 26 is open, the outlet valve 27 is closed, and the pressure of the oil in the supply tank is forcing the diaphragm toward the right against the bias of spring 56 to accumulate oil in the chamber 48. In this movement of the diaphragm 18, the bell crank lever 50 is being rotated in a counterclockwise direction which causes the stem 39 and the reed 36 thereon to move downwardly. As the crank arms 34 and 35 are engaged on their same sides by tines 36a and 36b, respectively, the downward movement of the stem 39 and reed 36 will not cause any rotation of the crank 30 but the arm 34 will deflect or bend the reed 36 transversely until the upper edge of tine 36a has passed below the lower edge of the arm 34. When the tine 36a has cleared arm 34, the then bent reed 36 will snap or whip the arm 35 through tine 36b in a counterclockwise direction about pivot 31, the width of the tine 36b being such that it still is in engagement with the arm 35. This causes the crank 30 to actuate the valve 26 to its closed position

and valve 27 to its open position, through the rod 29 and stem 25 against the bias of spring 33.

With the valves 26 and 27 in their new position, the oil in chamber 48 is then free to be expelled to the burner by means of the diaphragm 18 being biased toward the left by the spring 56. The rate at which the diaphragm 18 moves toward the left is controlled by the size of the opening of ports 65 and 66, the glycerin in chamber 67 or the air above the glycerin in said chamber being unable to flow into chamber 61 through the passage 62 due to the fact that the ball check valve 63 is closing said port 62. Thus, with the valve 72 in an open position, the position that it would have when it is desired to operate the burner to provide heat, the diaphragm 18 will deliver oil to the burner at a higher rate than if the valve 72 were closed and glycerin in chamber 67 were permitted to flow into chamber 61 only through the nearly closed port 65, as when only sufficient oil is desired to maintain a pilot flame. It might be observed at this time that all of the passages supplying oil are of substantial cross-sectional area which makes the oil flow less critical to changes in the viscosity of the oil than if there were restrictions in said passages. The metering of the oil delivery is thus controlled by the flow of a fluid, glycerin, or some other suitable fluid, which does not change the viscosity over a wide temperature range so that, practically, its rate of flow through the restricted ports 65 and 66 does not vary with temperature but solely by the position of the needle valves 71 and 72.

As the stem 39 starts to move upwardly under the bias of spring 56 acting through crank 50, the reed 36 will assume the position shown in Figure 3 of the drawing. The reed 36 which is then engaging the arm 35 on the left hand side thereof (as viewed in the Figure 3 of the drawing) will move up into engagement with the right hand side of the arm 34. Further upward movement of the reed 36 will tend to cause the reed 36 to leave the pin 35 but exert an increased pressure on the arm 34, which will continue to hold the crank 30 and the valve 26 down against the bias of spring 33. However, as the pin 34 cannot move counterclockwise due to the fact that it has reached its lower limit of travel, the reed 36 will be bent toward the right in gradually increasing amount until the lower edge of the tine 36a has cleared the upper edge of the arm 34. When this happens, the bent reed 36 will snap toward the left, as viewed in Figure 3, followed by the arm 35 as the arm 34 passes through the space between the tines 36a and 36b, under the bias of spring 33. It will be observed that when the spring 33 rotates the crank 30 about pivot 31 so as to move the arm 34 through said space, the valve 26 will be raised to its open position and the valve 27 to its closed position. It is thus seen that at each end of the travel of the diaphragm 18, the snap acting mechanism operates control valves 26 and 27 with a snap action alternately to their open and closed positions.

The elements of the metering device have now reached the position they assume at the start of a charging stroke. As the diaphragm 18 starts to move toward the right, tines 36a and 36b will move into engagement with the left hand side of the arm 34 as shown in Figure 2 of the drawing. Continued upward movement of the reed 36 under the action of diaphragm 18 will cause a repetition of the above described operation of the metering device.

It is deemed obvious that any suitable automatic and well known control means could be used to operate the valve 72 in response to room temperature to automatically place the metering device into operation.

As it is also obvious that various modifications may be made in the structure of the illustrated preferred embodiment of the invention, and that various substitution of equivalents may be made therein without departing from the spirit of the invention, it is to be expressly understood that the scope of the invention is to be determined solely by the appended claims.

I claim as my invention:

1. A fluid metering device comprising a housing having an inlet and an outlet, first and second chambers separated by a movable wall, said inlet and outlet being in communication with said first chamber, a third chamber having a plurality of passages extending therefrom to said second chamber, a liquid filling said second chamber and substantially filling said third chamber, a

check valve for permitting liquid flow through one of said passages from said second chamber to said third chamber but preventing reverse flow therethrough, at least one adjustable valve for regulating the rate of liquid flow through another of said passages, a control valve for alternately permitting liquid flow from said inlet to said first chamber and from said first chamber to said outlet, snap acting means operably connecting said control valve to said movable wall, and means biasing said wall in a direction to expel liquid from said first chamber and to move said control valve to the position permitting liquid flow to said first chamber from said inlet.

2. A fluid metering device comprising a housing having an inlet and an outlet, first and second chambers separated by a movable wall and a third chamber having a plurality of passages extending therefrom to said second chamber, a first valve seat between said inlet and said first chamber and a second valve seat between said first chamber and said outlet, a check valve for permitting fluid flow through one of said passages from said second chamber to said third chamber but preventing reverse flow therethrough, at least one adjustable valve for regulating the rate of fluid flow through another of said passages, a control valve for alternately engaging said first and second valve seats and means biasing said valve toward the second valve seat, means connecting said control valve to said movable wall, and means biasing said wall in a direction to expel fluid from said first chamber and to move said control valve against said second valve seat.

3. A fluid metering device comprising a housing having an inlet and an outlet, first and second chambers separated by a movable wall and a third chamber having a plurality of openings extending therefrom to said second chamber, passages extending from said inlet and outlet to said first chamber, a check valve for permitting fluid flow through one of said openings from said second chamber to said third chamber but preventing reverse flow therethrough, at least one adjustable valve for regulating the rate of fluid flow through another of said openings, a control valve for alternately connecting said first chamber to said inlet and said outlet through said passages, means connecting said control valve to said movable wall, and means biasing said wall in a direction to expel fluid from said first chamber and to move said control valve to a position connecting said first chamber to said inlet.

4. In a fluid metering device, the combination comprising a housing having first, second and third chambers, a movable wall between the first and second chambers and an apertured fixed wall between the second and third chambers, said first chamber having an opening therein, a control valve having an inlet and an outlet with a fourth chamber therebetween connected to said opening, said control valve having valve operating means connected to said movable wall, and resilient means normally biasing said valve operating means in a direction to move said movable walls to increase the size of the second chamber and to move said control valve in a direction to establish communication between said inlet and said fourth chamber while simultaneously closing said outlet, said movable wall being movable under inlet fluid pressure to a position closing said inlet and opening said outlet by said control valve.

5. In a fluid metering device, the combination comprising a housing having first, second and third chambers, a movable wall between the first and second chambers and an apertured fixed wall between the second and third chambers, said first chamber having an opening therein, a control valve having an inlet and an outlet with a fourth chamber therebetween connected to said opening, said control valve having valve operating means connected to said movable wall, biasing means normally biasing said valve operating means in a direction to move said movable wall to increase the size of the second chamber and to move said control valve in a direction to establish communication between said inlet and said fourth chamber while simultaneously closing said outlet, said movable wall being movable under inlet fluid pressure to a position closing said inlet and opening said outlet by said control valve, and snap-acting means controlling the movement of said control valve and operated by said movable wall.

6. In a fluid metering device, the combination com-

prising a housing having first, second and third chambers, a movable wall between the first and second chambers and an apertured fixed wall between the second and third chambers, said first chamber having an opening therein, a control valve having an inlet and an outlet with a fourth chamber therebetween connected to said opening, said control valve having valve operating means connected to said movable wall, means by which said valve operating means is normally biased in a direction to move said movable walls to increase the size of the second chamber and to move said control valve in a direction to establish communication between said inlet and said fourth chamber while simultaneously closing said outlet, said movable wall being movable under inlet fluid pressure to a position closing said inlet and opening said outlet by said control valve, and snap-acting means controlling the movement of said control valve.

7. A device for metering fluid comprising an accumulator having a movable wall, a control valve, snap acting means operable by said movable wall for actuating said control valve, an inlet and an outlet for said accumulator alternately opened and closed by said control valve, means biasing said movable wall in a direction to expel fluid from said accumulator when said outlet is open and said inlet is closed but operable under inlet pressure against said bias to permit said accumulator to fill when the outlet is closed and the inlet is opened, and means controlling the rate of movement of said movable wall in its expelling operation.

8. A device for metering fluid comprising an accumulator having a movable wall, a control valve, snap-acting means operable by said movable wall and operably connected to said control valve, an inlet and an outlet for said accumulator alternately opened and closed by said control valve, means biasing said movable wall in a direction to expel fluid from said accumulator when said outlet is open and said inlet is closed but operable under inlet pressure against said bias to permit said accumulator to fill when the outlet is closed and the inlet is opened, and means controlling the rate of movement of said movable wall in its expelling operation.

9. A device for metering fluid comprising an accumulator having a movable wall, a control valve operable by said movable wall, an inlet and an outlet for said accumulator alternately opened and closed by said control valve, means biasing said control valve in a direction to open said inlet, means biasing said movable wall in a direction to expel fluid from said accumulator when said outlet is open and said inlet is closed but operable under inlet pressure against said bias to permit said accumulator to fill when the outlet is closed and the inlet is opened.

10. In a fluid metering device, an accumulator having a movable wall, a double-headed valve member controlling the flow of fluid to and from said accumulator and operable by said movable wall, and snap-action means between said movable wall and said valve member comprising a crank having an actuating arm engaging said valve member and mounted on a pivot spaced from said valve member, a pair of parallel crank arms on said crank on opposite sides of said pivot, a non-rotatable rectilinearly slidably stem in a plane parallel to said crank, means operably connecting said movable wall to said stem, and a flat reed having a bifurcated end cooperable with said pair of crank arms for actuating said valve member, said reed being at substantially a right angle to said stem and connected at its other end to said stem with the plane of said reed at an acute angle to the axis of said stem.

11. In a fluid metering device, an accumulator having a movable wall biased in a direction to expel fluid from said accumulator, a double-headed valve member controlling the flow of fluid to and from said accumulator and operable by said movable wall, and snap-action means between said movable wall and said valve member comprising a crank having an actuating arm engaging said valve member and mounted on a pivot spaced from said valve member, a pair of parallel crank arms on said crank on opposite sides of said pivot, a non-rotatable rectilinearly slidably stem in a plane parallel to said crank, means operably connecting said movable wall to said stem, and a flat reed having a bifurcated end cooperable with said pair of crank arms for actuating said valve member, said reed being at substantially a right angle to said stem and connected at its other end

85

to said stem with the plane of said reed at an acute angle to the axis of said stem.

12. In a fluid metering device, an accumulator having a movable wall, a double-headed valve member controlling the flow of fluid to and from said accumulator and operable by said movable wall, and snap-action means between said movable wall and said valve member comprising means biasing said valve member in a direction to permit fluid flow into said accumulator, a crank having an actuating arm engaging said valve member and mounted on a pivot spaced from said valve member, a pair of parallel crank arms on said crank on opposite sides of said pivot, a non-rotatable rectilinearly slideable stem in a plane parallel to said crank, means operably connecting said movable wall to said stem, and a flat reed having a bifurcated end cooperable with said pair of crank arms for actuating said valve member, said reed being at substantially a right angle to and connected
